(57) **CLAIM**

The ornamental design for a fishing lure, as shown and described.

DESCRIPTION

FIG. 1 is a right side view of a fishing lure showing my new design;

FIG. 2 is a left side view of the fishing lure of FIG. 1;

FIG. 3 is a top view of the fishing lure of FIG. 1;

FIG. 4 is a bottom view of the fishing lure of FIG. 1;

FIG. 5 is a front view of the fishing lure of FIG. 1; and,

FIG. 6 is a rear view of the fishing lure of FIG. 1.

The broken lines in the Figures are for the purpose of illustrating unclaimed portions of the fishing lure and form no part of the claimed design.
